TELEGRAPHY SYSTEM WITH POSITION INDICATORS

Louis Lucien Eugene Chauveau, Paris, France, assignor to Compagnie Generale de Telegraphie Sans Fil, a corporation of France

Application February 20, 1934, Serial No. 712,130
In France February 20, 1933

1 Claim. (Cl. 177—311)

The present invention is concerned with a system insuring remote control of a mobile object and imparting at each instant the position of the mobile object thus controlled to the control station. It may be used in connection with the control and operation of radio-goniometers, projectors, turrets and other mechanisms in ship-board use, though the invention is not confined to these applications, indeed, it will be found useful everywhere in tele-control mechanic or signalling work:

One of the embodiments of the invention shall be hereinafter described by reference to the attached drawing. Fig. 1 of the drawing represents the apparatus to be mounted on the mobile object, while Fig. 2 shows the control station with position indicating means.

A movable object 1 (Fig. 1) which consists for instance, of a radio-goniometer loop 1 is driven by a motor 2 by means of a worm coupling 3. The loop 1 could thus be driven by a circular movement in either sense by the motor 2. The control electromagnets 4 and 5 which are adapted to reverse the direction of running of the motor are subject to control by the switch 6 of the remote control station Fig. 2.

In view of the fact that the loop 1 may turn a complete revolution, that is to say, turn through an angle of 360 degrees, the system has as its object to indicate at each instant at the control station, by means of direct reading, the exact position of the loop in terms of degrees. For this purpose the system comprises three sets of elements, to wit: the numerator, the translator, and the indicator. The first two means are placed in the neighborhood of the loop, while the indicator is mounted at the remote-control station.

The numerator comprises:

(1) A first distributor 7 which consists of six sectors upon which the brush or wiper 8 comes to be positioned sequentially the said brush being integral with the shaft of the coil and rotating at the same rate of speed as the latter, which shows that each of the contacts of the first distributor corresponds to 60 degrees of the circumference.

(2) Another distributor 9 similar to the one mentioned above; the wiper or brush 10 of this second distributor is connected with the shaft of the first one by way of a step-up gear 11 with a gear ratio of six to one, whence it results that the brush 10 turns six times faster than the brush 8; in other words, each contact of the distributor 9 represents ten degrees.

(3) A third distributor 12 comprises ten sectors, its brush 13 is united with the shaft of the second distributor 9 by means of a step-up gear 14 also of a gear ratio equal six to one; whence it follows that the brush 13 turns six times faster than the brush 10 and thirty-six times faster than the brush 8. In other words, each contact stud of distributor 12 thus represents 1 degree.

The brushes of the distributors are connected with the positive pole of a source of current, there being one wire for each contact terminal.

The wires of the first distributor 7 may be regarded as the wires of the hundreds, the wires of the second one 9 as the wires of the tens, and the wires of the third 12 as the wires of the units. It will at once be seen that the numerator has as its object the transformation of a continuous numeration from 0 to 360 degrees into a discontinuous one comprising six ciphers for the hundreds, six ciphers for the tens and 10 ciphers for the units. This makes it feasible to transmit by 6 plus 6 plus 10 conductors or a total of 22 the entire 360 indications that are required.

The translator is constituted by a relay assembly, the relays being fed by the wires of the numerator. This assembly has as its object the interpretation of the indications of the numerator and their translation into an unbroken numeration from zero to 360 degrees, this numeration being thereupon transmitted to the indicator by way of four wires for the hundreds, 10 wires for the tens and 10 wires for the units.

The translator device comprises:

(1) Six relays for the hundreds C1 to C6 fed by way of the wires of the first distributor 7.

(2) Six relays for the tens, D1 to D6, fed by way of the wires of the second distributor 9.

(3) Four short-circuiting relays CC1, CC1' fed by D1, and CC8, CC8' fed by D6.

(4) Two auxiliary relays A 5—6 and A 1—2.

(5) A zero relay ZO.

The part to be played by each one of these relays will be better understood after the following explanation:

Assuming that the loop has been stopped by switch 6, say, in the position corresponding to 225 degrees, brush 8 being positioned on contact 4, brush 10 upon contact stud 5, and brush 13 on the contact stud 5. As a matter of fact, it will be seen that the fourth contact stud of the first distributor corresponds to the range extending from 181 to 240 degrees, while the fifth contact of the second distributor covers the range from 221 to 230 degrees, and the fifth contact of the third 55

or last distributor corresponds then to the fifth degree of the last range, in other words, degree 225; the latter is thus transmitted under the form of number 455.

5 The relays C4 and D5 of the translator are then energized. With relay A 1-2 being at rest, the relay C4 will cause current to flow by way of terminal 2 of the hundreds. The relay C4 passes current also by way of the wire 14 through the 10 contact 15 of the relay D5 with the result that current is made to flow by way of terminal 2 of the tens; and at the same time, with brush 18 being positioned on stud 5, terminal 5 of the units is fed. It will thus be seen that the terminals that 15 are fed with current correspond to the number 225.

The terminals of the hundreds, tens and units of the translator are connected respectively and in sequence with the corresponding terminals 20 of the indicator (Fig. 2) each of these terminals is in the indicator united with a relay; whence it will be seen that in the indicator the relays RC2, RD2, and RU5 become energized, and these relays control each a numbered annunciator sight 25 with the result that the aggregate number 225 becomes visible.

It will be noted that these indications of position in terms of degree for the 360 degrees of the circumference described by the coil or loop 1 are 30 transmitted to the indicator by way of 4 wires for the hundreds, 10 wires for the tens, and 10 wires for units, in other words, a cable comprising 24 conductors. This cable may be of small diameter 35 of the type used in telephone work.

35 Fig. 2 shows but part of the receiving relays for the tens and the units, for the sake of simplification of the scheme; for it will be understood that the equipment in actuality contains 10 relays RD and 10 relays RU.

40 The difficulty arising in carrying such a system into practice results from the fact that since continuity of indication is lacking it is necessary that the brushes of the distributors should be so designed wide enough so as to overlap or straddle 45 two successive contact sectors at the instant of changing from one sector to another; it is aggravated by the circumstance that the mobile object may be driven in one direction or the other. Now, the object of the relays CC1, CC1', 50 CC6, CC6' and ZO is to overcome this difficulty as will be better understood from the explanations to be given hereinafter on this score.

Suppose that loop 1 and the distributors rotate in the direction of the arrows and that 55 the brush 8 rides on contact studs 3 and 4 at the moment when the brush 10 is still positioned on contact 6. The relay D6 is then energized, it feeds relays CC6 and CC6' which are rendered operative. At this instant the brush 8 by contact 60 4 tends to feed C4, but C3 and CC6 are energized and by the contacts 16 and 17, C4 is short-circuited. However, no short-circuiting of the source takes place owing to the presence of resistance r4 uniting C4 with the negative pole. It 65 will be seen that C3 remains only energized as long as brush 10 is positioned on sector 6.

70 However, at the instant when brush 10 overlaps partly contacts 6 and 1 the relay D1 is energized; it breaks by action of its contact 18 the circuit of D6 which comes to a stop rendering inoperative CC6 and CC6'. C4 is no longer short-circuited and is made operative. At the same time, D1 by its contact 19 feeds CC1 and CC1' 75 which operate; the relay C3 is then short-circuited

by the contacts 20 of C4 and 21 of CC1', and relay C3 comes to rest.

At the instant D1 operates, the brush 10 overlaps partly studs 6 and 1, the contact 18 changes into the working position, resulting in relay ZO 5 being energized; the latter cuts off the wire for unit 9 and renders the conductor for 0 alive.

It will thus be seen that the number 410 has come to take the place of number 369 at the very instant when the brush 10 reaches the sector 1 regardless of where the brushes may straddle.

Suppose then, that the loop 1 and the various distributors rotate in the inverse direction to what has been indicated by the arrows and that brush 8 straddles the same contacts 4 and 3; at 15 the instant when the brush 10 is still on contact 1. The relay D1 is then energized, it feeds the relays CC1 and CC1' which are thus rendered operative. At this moment the brush 8 by way of contact stud 3 tends to feed C3, but C4, CC1 and 20 CC1' are energized, while by way of contact 20 of C4 and contact 21 of CC1' the relay C3 is short-circuited. C4 only stays energized while the brush 10 is on sector 1.

When brush 10 is astride contacts 1 and 6, 25 the relay ZO operates and indicates zero.

When the brush 10 leaves sector 1, D1, CC1 and CC1' come to be deenergized as well as ZO; C3 being no longer short-circuited comes to operate at the same time as D6 is energized whence operation of CC6, CC6' short-circuiting of C4 by way of contacts 16 and 17.

It will thus be noted that the number 369 has taken the place of number 410 at the very instant when brush 10 leaves the sector 1. What follows 35 from the foregoing description is that the part played by the relays CC1, CC1', CC6, CC6' and ZO consists in insuring a change in numeration at a precise point at the instant when brushes straddle. This particular feature in the construction 40 allows of easier manufacture of the numerating means, it assures precise transmission of the indications in the absence of any break.

The part played by relays A 5-6 and A 1-2 is to insure suitable feeding of the terminals of the 45 hundreds according to the position of the numerator.

In fact, sector 1 of the first distributor 1 covers the range from 1 to 60 degrees which corresponds always to the figure 0 of the hundreds; it is for 50 this reason that the contact 22 of C1 feeds always terminal 0 of the hundreds. But sector 2 corresponds to the range extending from 61 to 120 degrees; hence by way of C2 it must feed terminal 0 of the hundreds during the passage of the 55 first four tens and terminal 1 of the hundreds during the passage of the last two tens. Now, the relay A 5-6 is in series with the relays D6 and D6, this relay directs the wire brought from contact 23 of C2 towards the terminal 0 during 60 the first four tens and to terminal 1 during the last two tens.

Relay A 1-2 plays the same part in reference to contact 24 of relay C4, but it is connected in series with D1 and D2 since the sector 4 corresponds to the range extending from 181 to 240; 65 its first two tens form part of hundreds 1, its last four tens are part of hundreds 2.

What follows from the foregoing description is that the tele-mechanical control system comprising position indicating means as just disclosed allows of the remote control of a movable object, while imparting to the control station by direct reading a degree by degree knowledge of the position of the said mobile object at each instant 70 75

under consideration; it requires only for control and the indications corresponding to 360 degrees the use of a cable containing 26 conductors, whereof two are for control action and 24 for the 5 signaling, to be installed between the control point and the object to be controlled. The said cable could be of the kind used in telephone work as stated, of reduced cross-sectional size. The use of such a cable will not be prohibitive for tele- 10 mechanical controls extending over short distances, say, of an order of one hundred meters or so involved on shipboard.

Where equipments involving greater distances are concerned, the same in addition will comprise, 15 as shown in Fig. 2, repeaters of the potentiometer or Wheatstone bridge types. Each of the hundreds relays of the indicator (RC0 to RC3) has its contact associated with a resistor or voltage divider PC feeding a galvanometer GC. 20 Similarly the relays of the tens (RD0 to RD9) are united with a voltage divider PD feeding a galvanometer GD, and the units relays (RU0 to RU9) are associated with a voltage divider PU feeding a galvanometer GU.

25 The indicator will be placed like the numerator and translator in the neighborhood of the movable object to be controlled.

The control station comprises only the switch 6 and the three galvanometers repeating the indications of the indicator; in that instance, eight wires will suffice between the control station and the mechanism subject to control action though this number could be reduced to six by using a point common to the three galvanometers. This 30 system makes it feasible to preserve the features of direct and instantaneous reading.

It will be clear that the foregoing embodiment is merely described by way of example and has nothing limitative about it. Indeed, it is possible 35

to enlarge the number of the indications by the addition of one or more distributors giving fractions of degrees in decimals (tenths, hundredths, etc.).

The subdivision of the indications in six groups 5 of six tens has been suggested by way of example and for the sake of argument as an easy realization in a case of indications on the 360-degree basis. But this subdivision could be varied according to any given case. 10

While I have described a particular form of my invention it should not be so limited except such limitations as are clearly imposed in the appended claim. 15

I claim:

Apparatus for controlling a movable member remotely located from a control and indicating station having indicating means to indicate the position of said movable member, comprising a reversibly controlled motor for driving said movable member to be controlled through different degrees of rotation, means coupled to said motor for driving a distributor mechanism through ratio gearing means to make and break contacts proportional to hundreds, tens and units degrees of rotation of said controlled member, said contacts being made to select and energize corresponding conductors leading to said control and indicating station, where said energized conductors control corresponding relays to establish potential drops 30 across corresponding resistors and excite separate indicators in proportion to the hundreds, tens and units degrees of rotation of said controlled member, and means for simultaneous readings of the separate indicators to give an indication in degrees of the then obtained angular position of the controlled member. 35

LOUIS LUCIEN EUGENE CHAUVEAU.
